COMBINED PRODUCE DISPLAY AND SCALE STAND

Edwin F. Schild, Schiller Park, Ill.

Application May 28, 1954, Serial No. 30,735

Term of patent 14 years

(Cl. D80—9)

Fig. 1.

Fig. 2.

Fig. 3

Fig. 4.

To all whom it may concern:

Be it known that I, Edwin F. Schild, a citizen of the United States of America, residing at Schiller Park, county of Cook, State of Illinois, have invented a new, original, and ornamental Design for a Combined Produce Display and Scale Stand, of which the following is a specification, reference being had to the accompanying drawing, forming a part hereof.

Fig. 1 is a top plan view of a combined produce display and scale stand embodying my new design; Fig. 2 is a front elevational view; Fig. 3 is a side elevational view and Fig. 4 is a perspective view of the same.

I claim:

The ornamental design for a combined produce display and scale stand, substantially as shown.
